Attorney

UNITED STATES PATENT OFFICE.

ALBERT E. MAYNARD, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

GRINDSTONE.

Application filed December 4, 1926. Serial No. 152 554.

This invention relates to improvements in grindstones and has particular reference to a split or divided grindstone for grinding bevel edges.

5 The principal object of this invention is to provide improved means for separating a divided or split grindstone so that it may be trued.

10 Another object of the invention is to provide simple and efficient means for holding together in aligned position the portions of a divided or split grindstone.

15 Another object of the invention is to provide simple and efficient means for truing a bevel grooved grindstone in which the bevelled parts of the stone may be separated.

20 Other objects and advantages of the invention will become apparent from the following description taken in connection with the accompanying drawings and it will be understood that many changes in the details of construction and arrangement of parts may be made without departing from the spirit of the invention as expressed in the accompanying claims. I, therefore, do not wish to be limited to the exact details of construction and arrangements shown.

25 Referring to the accompanying drawings: Figure 1 is a front elevation of a mounted grindstone embodying the invention;

30 Figure 2 is a fragmentary cross sectional view on line 2—2 of Figure 1;

Figure 3 is a top or plan view of Figure 1 shown partially in section.

35 Prior to my invention bevel grooved grindstones have been made in one piece with a bevel groove in the periphery. It has been found from experience that it is difficult to true such a stone due to the fact that the truing is not correct in the bottom of the groove. It has also been found that such a stone is not exactly accurate in its grinding properties due to the fact that the bottom of the groove cannot be perfectly made in such a stone.

40 It is the object of my invention, therefore, to overcome these difficulties of grinding and of truing by simple and efficient arrangements of separating the stone on the division line at the bottom of the groove.

45 Referring to the drawings wherein similar characters denote corresponding parts

throughout, a grindstone 1 made in two halves 2 and 3 and having the bevelled faces 4 and 5 is mounted on a shaft 6 in the bearings 7 and 8. The grindstone is turned by the pulley 9 and the belt 10 in the usual manner. The sections 2 and 3 of the grindstone 1 are mounted on a hub or carrier 11. The section 3 is directly secured to the hub 11 by means of an adhesive strip 12 while the section 2 is slidably connected to the hub 12 by means of the adjusting collar 13 to which it is secured by an adhesive strip 14. The adjustable collar 13 is screw threaded at 15 to the hub 11 and has in its periphery, openings 16 for a spanner or other wrench connection. The section 2 may be advanced by turning the collar 13 until it engages the section 3 making in effect a complete bevel edge grindstone having the bevels 4 and 5. By reversing the action of the screw collar 13 the parts 2 and 3 may be separated. The hub 11 is secured to the shaft 6 by means of the key 17 so that the grindstone members 2 and 3 rotate with the shaft 6.

50 When the parts of the stone 2 and 3 are separated as shown in Fig. 3 the section 2 is locked against rotation on the collar 11 by means of the set screw 18 which is tightened up after the section 2 has been brought to the position shown in Fig. 3. This is done so that the truing of the stone may be carried on as described hereinafter without having the section 3 rotate on the screw thread of the hub 11.

55 The bevel edges 4 and 5 of the stone sections 2 and 3 respectively are trued by a diamond point 19 held in place on the truing rod 20 which slides in the guide members 21. The guide members 21 are secured to a base plate or frame 22 which in turn slides in the slide way 23 on the base 24 of the grindstone frame. The plate 22 is advanced towards or withdrawn from the grindstone by means of the screw 25 having the turn nut 26. The truing rod 20 has a handle 27 by which the truing rod may be slid longitudinally in the guide 21 to advance it towards the stone or withdraw it therefrom, the guides 21 being related to the grindstone on the angle of the bevel faces of the stone one on each side. The truing rod 20 is retained in place in the guides 21 by means of the collar 28 which is located in

place by the set screw 29 and which may be turned by the handle 30. The truing rod 20 is prevented from turning in the guides 21 by means of the pin 31, the pin operating in the groove 32 in the guides 21. The diamond 19 is mounted on a pivoted head 33 by means of the set screw pivot 34 by which the diamond point 19 may be set at the proper cutting angle to the bevel face of the grindstone. 10 In the truing operation the frame 22 is advanced by means of the screw 25 to proper position with relation to the grindstone faces and the truing rod 20 pushed back and forth in the guides 21 during the truing operation, this pushing back and forth being done by hand. When one side, such as the portion 3 of the grindstone shown in Fig. 3 has been completed the truing rod 20 with its diamond point 19 is transferred to the guides 21 on the opposite side and the operation gone through as above only to the opposite hand. In this way each side of the stone may be trued to the proper bevelled face. It will be understood that before this truing operation is performed the two portions of the stones 2 and 3 are separated by the collar 13 as described and after the truing operation has been done the two sections 2 and 3 are brought up to bear one against the other as shown in Fig. 1. The section 2 is prevented from turning by means of the set screw 18 which tightens the collar 13 on the hub 11. The diamond or cutting point 19 is locked in position by the screw pivot 34 with a screw driver, the screw having the regular screw head slot.

From the foregoing description it will be seen that I have provided a simple, efficient and economical means for producing a divided bevel grindstone wherein the parts may be readily separated or locked together and wherein the parts may be accurately and efficiently trued, thus insuring proper trueness of the groove at its bottom so that the work that is being bevelled in the groove will have a true apex.

Having described the invention, I claim:

1. A bevelled edge grinding machine comprising a base, a shaft rotatably mounted on the base, a grindstone holding hub on the shaft, a sectional grindstone member on the hub having an angled grinding edge, a second sectional grindstone member movably mounted on the hub and having an angled grinding edge, the diameters of the adjacent faces of the grindstone members being shorter than those of the outer faces, means for locking the second grindstone member on the hub in spaced relation to the first grindstone member, guide way members on the base having truing tool guides parallel to the respective angled grinding edges of the grindstone members whereby each angled face of the grinding edges of the grindstones may be trued by a

truing tool in the truing tool guide when the sections of the grindstones are separated and both sections locked with respect to the shaft. 65

2. A bevelled edge grinding machine comprising a base, a shaft rotatably mounted on the base, a grindstone holding hub on the shaft, a sectional grindstone member on the hub having an angled grinding edge, a second sectional grindstone member movably mounted on the hub and having an angled 70 grinding edge, the diameters of the adjacent faces of the grindstone members being shorter than those of the outer faces, means for locking the second grindstone member on the hub in spaced relation to the first grindstone member, guide way members on the base having truing tool guides parallel to the respective angled grinding edges of the grindstone members whereby each angled face of the 75 grinding edges of the grindstones may be trued by a truing tool in the truing tool guide when the sections of the grindstone are separated and both sections locked with respect to the shaft, and means to move the truing tool guides on the base towards and away 80 from the grindstone sections. 85

3. A bevelled edge grinding machine comprising a base, a shaft rotatably mounted on the base, a grindstone holding hub on the shaft, a sectional grindstone member on the hub and having an angled grinding edge, a second sectional grindstone member movably mounted on the hub and having an angled 90 grinding edge, the diameters of the adjacent faces of the grindstone members being shorter than those of the outer faces, means for locking the second grindstone member on the hub in spaced relation to the first grindstone member, guide way members on the base having truing tool guides parallel to the respective angled grinding edges of the grindstone members, and a separable truing tool in one 95 of the truing tool guide-ways. 100

4. A bevelled edge grinding machine comprising a base, a shaft rotatably mounted on the base, a grindstone holding hub on the shaft, a sectional grindstone member on the hub having an angled grinding edge, a second sectional grindstone member movably mounted on the hub and having an angled 110 grinding edge, the diameters of the adjacent faces of the grindstone members being shorter than those of their outer faces, means for locking the second grindstone member on the hub in spaced relation to the first grindstone member, guide way members on the base having truing tool guides parallel to the respective angled grinding edges of the grindstone members, a truing tool in one of the truing tool 115 guide ways, and means to move the truing tool guides on the base towards and away 120 from the grindstone sections. 125
